United States Patent Office

Des. 202,440
Patented Sept. 28, 1965

202,440

LUMINAIRE

Myron F. Pettengill, Hendersonville, N.C., assignor to
General Electric Company, a corporation of New York

Filed June 3, 1964, Ser. No. 80,267

Term of patent 14 years

(Cl. D48—31)

FIGURE 1 is a front elevational view of a luminaire embodying my new design;

FIGURE 2 is a top plan view thereof;

FIGURE 3 is a bottom plan view thereof;

FIGURE 4 is a side elevational view thereof as seen from the right of FIGURE 1; and

FIGURE 5 is a fragmentary vertical section as viewed in FIGURE 1.

The broken line showing is for illustrative purposes only.

I claim:

The ornamental design for a luminaire, as shown and described.
